FEEDING MECHANISM FOR CLOTH PILING MACHINES AND THE LIKE

Filed July 6, 1928

FIG. 1

Inventor
John S. Lyth
of Boston, Mass.

UNITED STATES PATENT OFFICE

JOHN J. LYTH, OF VALLEYFIELD, QUEBEC, CANADA

FEEDING MECHANISM FOR CLOTH-PILING MACHINES AND THE LIKE

Application filed July 6, 1928. Serial No. 290,865.

This invention relates to improvements in means for feeding continuous lengths of material such as roped cloth into any device, such as a kier piler, located beneath the feeding means.

The primary object of the invention is to enable the material to be fed at high lineal speed and with such great accuracy as to enter the receiving device exactly at a pre-determined point.

A further object of the invention is to provide means for adjusting the feeding device to compensate for changes in the direction of material coming to it and to change the direction of material leaving it, both adjustments serving to secure the accuracy of delivery previously mentioned.

A still further object is to provide for easily passing knots or snarls which are found in roped cloth and similar material.

Various other objects and the advantages of the invention may be ascertained from the following description.

In textile mills, piling machines are coming into general use to expedite the filling of kiers. It frequently happens that introduction of piling machines leaves but little headroom under a ceiling in which to place winces or other cloth feeding devices so that the diameter of feeding drum must frequently be less than usual. This circumstance coupled with the greater lineal speed of cloth to be obtained compels a very high angular speed in the feeding device and, in consequence, a centrifugal effect is obtained which causes the cloth rope to leave the feeding drum. These conditions place such a limit upon the angular speed that it becomes impossible to realize a desired lineal speed of cloth feed.

Furthermore, at high lineal and rotative speeds, it is difficult because of centrifugal effect to control the point of departure of cloth from the feed roll which determines the direction of the cloth passing from the feeding device to the piling or other mechanism. If the cloth is not properly directed, it tends to and frequently does reach the piling or other receiving means at an improper point and piles up on the machine,

thus necessitating frequent stoppings to clear the machine. This greatly lowers the efficiency of the machines.

In addition to all the foregoing, a change in the direction of approach of the cloth to the feeding means will shift the point at which the cloth leaves the feeding roll along the roll, so that misdirection of cloth may result from this cause also with disadvantage as previously explained.

According to this invention, mechanism of a size suitable to the restricted space available, adapted to feed cloth accurately and at high lineal speed, comprises essentially a feed roll of small diameter, adapted to operate at high angular speed, mounted in vertically adjustable bearings, a keeper roll associated with and urged toward the feed roll, driving means for the feed roll including a slipping clutch, and an adjustable eye to guide cloth to the feed roll.

In the accompanying drawings which illustrate one embodiment of the invention, but to which embodiment and the details thereof the invention is not confined;

Fig. 1 is a side elevation of the cloth feeding means.

Fig. 2 is an elevation of the entrance end of the device (the left hand end in Figure 1).

Referring more particularly to the drawings, 11 designates a feed roll of relatively small diameter adapted to be operated at high angular speed so as to impart high lineal speed to cloth passing thereover. The roll is fixed to a shaft 12 mounted in bearings 13 vertically adjustable on depending threaded posts 14 forming part of a bracket 15, the adjustment being secured by nuts 16 co-operating with the posts above and below the bearings.

An idle keeper roll 17, preferably of less diameter than the feed roll, is associated therewith and is mounted on a shaft 18 parallel with the shaft 12 and journalled in the lower end of a rigid frame comprising arms 19 fixed to a bar 20, the ends of which are journalled in lugs 21 springing from the upper part of the bracket 15. The location of the lugs 21 and the length of the arms

19 are such that when the bearings 13 are located midway of the length of the posts 14, the axes of the shafts 12 and 18 are (allowing for thickness of cloth between the rolls) in the same horizontal plane.

5 The rolls 11 and 17 are preferably provided with coverings 22 of rubber or other suitable material adapted to afford a good grip on the cloth and at the same time to avoid injury thereto.

10 The roll 17 is urged toward the roll 11 by any suitable means, such as helical springs 23 tensioned between the arms 19 and the remote posts 14 or other suitable parts of the device.

15 On the opposite side of the feed roll from the keeper roll, a cloth guiding eye 24 of any usual or suitable form is provided and is mounted in an arm 25 pivoted to a bracket 26 and adapted to be adjusted in a vertical plane parallel with the axis of the roll. The contacting portions 27 of the arm and bracket are toothed for inter-engagement to secure the arm in any desired adjustment 20 and the arm is provided with a threaded stud 28 passing through the bracket (which stud may if desired serve to pivotally connect the arm and bracket) and carrying a nut 29 to bear against the bracket and clamp the toothed portions together.

25 One end of the feed roll shaft 12 preferably projects beyond the bearing and carries a driving pulley 30 connected thereto by a slipping clutch comprising a sleeve 31 fixed to the shaft and having a flange 32 bearing against one side of the web 33 of the pulley; a second sleeve 34 splined on the sleeve 31 and having a flange 35 bearing against the other side of the pulley web 33; and a spring 36 in compression between the outer or unflanged end of the sleeve 34 and an abutment 37 on the sleeve 31, which may conveniently be one or more nuts screwed on the end of the sleeve 31.

30 Cloth in roped form or other material, designated 38, passes through the eye 24 over the roll 11 and downwardly between the rolls 11 and 17 to a piling machine, kier or other receiver designated 39.

35 Normally, the material is to be considered as coming to the feeding device in a path extending at right angles to the shaft 12 and intersecting the roll midway of its ends. Under such condition, the eye 24 is centered in medial transverse plane of the roll 11, as shown in Figure 2, and the cloth will pass over the roll midway between the ends thereof. If the source of the cloth changes, as frequently happens, and it approaches the roll at an acute angle, it shifts in the eye from a central position at the top to a position at one side with the result that it would pass over the roll toward one end thereof and thus alter the point of departure from the roll. To avoid this, the eye 24 is adjusted

40 away from the source of the cloth until the cloth passes over the roll midway between the ends thereof; the adjustment being effected by loosening the nut 29, swinging the arm 25 and again tightening the nut.

45 The idler or keeper roll 17 serves to hold the cloth in contact with the feeding roll 11 against the action of centrifugal force tending to cause the cloth to fly away from the roll and, in this way, the desired lineal speed of movement is imparted to the cloth in spite of the high angular speed of the roll. The idler roll further determines the point in the circumference of the feed roll at which the cloth leaves the roll, and thereby determines the direction of the cloth. The cloth will leave the roll in a direction normal to the plane containing the axes of the shafts 12 and 22, so that when these shafts are in the same horizontal plane the cloth will drop vertically from the rolls. If the cloth does not fall exactly as desired into the receiving element 39, the roll 11 may be adjusted upwardly or downwardly by means of the nuts 16. By combined adjustment of the roll 11 and eye 24, the cloth may be directed to arrive at any given point in the receiving device 39. The yielding pressure of the roll 17 and the resilient covering of the rolls ensures against damage to the cloth 50 and enables the passing of knots connecting the lengths of cloth which make up the rope. Owing to the high lineal speed at which the cloth is handled and the effective traction of the roll 11 (due to the roll 17), even momentary interruption in the supply of cloth to the feeding device would with an inflexible drive cause such tension in the cloth that breaking of the rope or damage to the cloth is likely.

55 The slipping clutch provided between the pulley 30 and shaft 12 guards against cloth breakage by providing a flexible drive, the tension of the spring 36 being adjusted to provide only a slight excess of friction between the flanges 32, 35 and the pulley web over that required to transmit the power necessary to feed the cloth under normal conditions. If there is any interruption in the supply of cloth, the clutch merely slips. This slipping also occurs if a knot or snarl comes to the rolls and will not pass between them.

60 Having thus described my invention, what I claim is:—

65 1. In feeding mechanism for cloth piling machines and the like, in combination with a receiving device, a horizontal feed roll above the receiving device to supply material thereto, an idler roll urged toward the feed roll and adapted to hold material in contact with the feed roll, the feed roll being vertically adjustable relatively to said idler to determine the point of departure and direction of material leaving the feed roll whereby the material will be di- 70 75 80 85 90 95 100 105 110 115 120 125 130

rected to any desired point of the receiving device.

2. In feeding mechanism for cloth piling machines and the like, in combination

5 with a receiving device, a horizontal feed roll above the receiving device to supply material thereinto, an idler roll associated with the feed roll axially parallel thereto, said rolls being relatively adjustable in vertical direction to determine the point of departure of material from the circumference of the feed roll, whereby the material will be directed to a predetermined point of the receiving device.

10 3. In feeding mechanism for cloth piling machines and the like, in combination with a receiving device, a horizontal feed roll above the receiving device to supply material thereinto, an eye through which material coming to the feed roll passes, said eye being adjustable along the roll to determine over what part in the length of the roll the material will pass, and an idler roll on the opposite side of the feed roll from 15 said eye, said rolls being arranged axially parallel and relatively adjustable in a vertical direction to determine the point of departure of material from the circumference of the feed roll, the adjustments of said eye and rolls enabling the material to be directed to any desired point of the receiving device.

20 4. In feeding mechanism for cloth piling machines and the like, in combination with a receiving device, a horizontal feed roll above the receiving device adapted for rotation at such high angular speed that the material would leave the roll by centrifugal force without acquiring the desired lineal speed, an eye close to the feed roll at a level below the axis of the feed roll through which eye material passes to the feed roll, an idler roll on the opposite side of the feed roll from the eye, said rolls being located approximately 25 at a common level, and means to urge the idler roll toward the feed roll, said eye and idler roll co-operating to hold material in contact with the feed roll through approximately half the circumference thereof in opposition to centrifugal force whereby the material will attain the desired lineal speed.

30 5. In feeding mechanism for cloth piling machines and the like, a bracket, a horizontal feed roll vertically adjustable in the bracket, a frame pivoted to the bracket, an idler roll journalled in the frame and thereby held axially parallel with the feed roll, and means to urge the idler roll toward the feed roll.

35 6. In feeding mechanism for cloth piling machines and the like, a feed roll, a bracket, an arm pivoted at its upper end to the bracket at a level above the roll and adapted to swing lengthwise of the roll, an eye carried 40 by the lower end of said arm through which

eye material passes to the roll, and means to secure the arm at various angles thereby to determine over what part in the length of the roll the material will pass.

7. In combination with a device according 45 to claim 4, a friction drive for the feed roll adapted to supply substantially only the power required to move the material and to slip upon interruption in the supply of material to the feed roll thereby to prevent 50 breakage of the material.

In witness whereof, I have hereunto set my hand.

JOHN J. LYTH.
